DESIGN FOR AN ILLUMINATED ADVERTISING DISPLAY DEVICE

Herbert O. Sperry, Drexel Hill, Pa.

Application May 14, 1938, Serial No. 77,192

Term of patent 3½ years

To all whom it may concern:

Be it known that I, Herbert O. Sperry, a citizen of the United States, residing in Drexel Hill, Delaware County, State of Pennsylvania, have invented a new, original, and ornamental Design for an Illuminated Advertising Display Device, of which the following is a specification, reference being had to the accompanying drawing, forming part thereof.

Figure 1 is a side perspective view of an illu-

minated advertising display device, showing my new design.

Figure 2 is a bottom view of the pendent portion shown in Figure 1.

Figure 3 is a front elevational view of Figure 1.

I claim:

The ornamental design for an illuminated advertising display device, as shown.

HERBERT O. SPERRY.
